UNITED STATES PATENT OFFICE.

WILLIAM EISELE, OF MARION COUNTY, INDIANA.

IMPROVEMENT IN FINGER-RINGS.

Specification forming part of Letters Patent No. 175,057, dated March 21, 1876; application filed February 18, 1876.

To all whom it may concern :

Be it known that I, WM. EISELE, of Marion county, State of Indiana, have invented a new and useful Adjustable Ring, of which the following is a description, reference being had to the accompanying drawings.

My invention consists of forming a ring in sections so arranged as to be readily adjusted to suit the size of the finger on which it is placed.

Figure 1 represents an edge view of a finger-ring embodying my improvement. Fig. 2 is a side view of the same, partially in section, showing the arrangement and position of the different parts. Fig. 3 is a view of the lower section, or that part that encircles the under portion of the finger. Fig. 4 is a side view of the ornamented side hinged piece, provided with a pin.

A represents that part of the ring that encircles the lower or inside part of the finger, the two ends of which are perforated with a number of holes, P, as shown, the operation of which will be described hereafter. The upper part of the ring is formed with a case, B B', on each side, into which fit the ends of the lower part A, as shown in Fig. 2.

On the outside of these cases B B', near the center above, is hinged the ornamental side

catches C, which are provided with pins D, as shown more fully in Fig. 4.

To adjust my improved ring upon the finger, first raise up the hinged catch C, which will remove the pin D from the holes P in the lower section A, and then slip the section A either in or out, as required, to make the ring large or small; when properly adjusted, close the hinged catches C, when the pin D will enter one of the holes P and hold the sections firmly together, as shown in Figs. 1 and 2.

What I claim as new, and wish to secure by Letters Patent, is—

As a new article of manufacture, a finger-ring composed of the section A, perforated at each end with holes P, the cases B B' arranged to receive the section A, and the hinged ornamented catch C, provided with a pin D, all arranged to operate in the manner shown for the purposes set forth and described.

In testimony whereof I have signed my name to this specification in the presence of two subscribing witnesses.

WILLIAM EISELE.
